GAME APPARATUS

John K. Stafford, Pittsfield, Mass.

Application October 30, 1933, Serial No. 695,753

12 Claims. (Cl. 273—35)

My invention relates to games and more particularly to apparatus, relating to the game of golf, which enables a golf stroke to be executed with a standard full sized club and ball in a space which need not necessarily be much larger than the space required for swinging a club. This apparatus may either be used as part of a game or it may be used as a device for practicing the golf stroke. If the apparatus is to be used as part of a game, it may be used, by way of example, in connection with a fictitious golf course which could be laid out in an instruction book.

The three quantities which mainly concern one who plays a golf shot are distance, direction and amount of hook or slice. In accordance with my invention I provide an extremely simple and inexpensive device for indicating all three of these quantities and which can be used in a space but little larger than that required to swing a golf club.

An object of my invention is to provide a new and improved game apparatus.

Another object of my invention is to provide a golf practice device which is extremely simple and inexpensive to construct.

A further object of my invention is to provide a new and improved golf practice device which will give indications of the distance, direction and amount of hook or slice which result from an actual golf stroke.

My invention will be better understood from the following description, taken in connection with the accompanying drawing, and its scope will be pointed out in the appended claims.

In the drawing, in which similar reference characters designate similar elements throughout the several views, Fig. 1 is a perspective view of a preferred form of my invention in its normal state of rest prior to being used, Fig. 2 is a perspective view showing the position of the parts after a stroke has been taken, Fig. 3 is a cross-section through the golf ball showing the details of its mounting, Fig. 4 is an enlarged plan view of the portion of the apparatus for indicating the amount of hook or slice, and Fig. 5 is a detailed cross-sectional view of the apparatus on the line 5—5 of Fig. 1.

Referring now particularly to Fig. 1 of the drawing, it will be seen that the illustrated embodiment of my invention consists essentially of a trough or channel 1, preferably constructed of metal, and preferably provided with inwardly sloping side walls 2. The trough 1 is pivotally mounted for rotation in a horizontal plane by any suitable means, such, for example, as by a

nail 3 passed through a hole in the bottom of the trough at one end thereof and driven into the ground or any other suitable support for the device. Inside the trough is mounted a length of flexible or resilient material, such, for example, as a length of collapsed rubber tubing 4 which is substantially as long as the trough, and whose normal width is preferably greater than the shortest distance between the side walls 2. Inside the tube 4 is another length of flexible material, such, for example, as a length of oak leather 5. The oak leather strip 5 extends out of each end of the rubber tube 4 and the end thereof adjacent the pivotal support, that is to say, the right-hand end as shown in the drawing, is fastened to a golf ball 6 by any suitable means, such, for example, as by a piece of flexible leather 7 which is fastened to the oak leather strip 5 by any suitable means, such as by rivets or rawhide lacing 8.

The side walls 2 may either be an equal distance apart throughout their length, or they may be drawn progressively nearer together from right to left, or they may be drawn progressively nearer together from left to right. I at present prefer to have the side walls drawn progressively nearer together from right to left, as the apparatus is viewed in Figs. 1 and 2 of the drawing, but this is a matter of relatively small importance.

As shown in detail in Fig. 3, the ball 6 is supported for rotation about a normally substantially vertical axis by means of a pin or stud 9 which is fastened to the flexible leather strip 7 by means of a transverse pin 10 passing through stud 9 and fastened firmly to the strip 7 by any suitable means, such as by stitching or rivets. The stud 9 is provided with a relatively large, flat head 11 and the shank portion of the stud is circular in cross-section and is preferably tapered so as to be smaller in diameter at the top than at the bottom. The ball 6, being preferably a standard golf ball, is resilient and consequently stud 9 is preferably made of one piece and can be forced through the ball from top to bottom and then inserted in the strip 7 by means of the pin 10. As will be explained more in detail later it is desirable to have a relatively tight frictional fit between the ball 6 and the stud 9.

The ball 6 is preferably provided with a plurality of distinctive marks, such as differently colored or differently marked, stripes 12, one of which acts at a time as a suitable pointer for cooperation with a hook or slice indicating scale 13 marked on top of the head 11, as is shown in detail by Fig. 4.

The other or left-hand, end of the leather strip 55

5 is preferably formed in the shape of a pointer 14 for cooperation with a suitable scale member 15 for indicating initial direction of flight of the ball.

5 The inside bottom surface of the trough 1 is provided with a scale 16 preferably calibrated in yards for indicating the distance of a practice golf shot. The flexible members 4 and 5 are preferably fastened to the trough 1 by any suitable 10 means, such as a machine screw 17 provided with a washer 18 and nut 19, as is clearly shown in Fig.

15 This is desirable in order to secure an accurate registration of distance, for otherwise the flexible elements will either pull out of the trough 15 entirely under a heavy blow, or else they will slide along the trough, thus giving an uncertain 20 distance indication.

The operation of the above described embodiment of my invention is as follows: If the golf ball 20 6 be squarely struck by a golf club, from right to left as viewed in the drawing, along the axis of the trough 1, the ball will of course rise depending upon the amount of loft of the club and in moving from right to left will pull the flexible 25 members 4 and 5 out of the trough 1 as is clearly shown in Fig. 2. This pulling of the flexible members 4 and 5 out of the trough 1 is retarded by the sloping sides 2 which offer a more or less uniform resistance to this action with the result that 30 the amount of flexible material which is pulled out of the trough is an indication of the horizontal component of the force with which the ball has been struck. Due to this uniform frictional retarding action the ball will normally come to 35 rest before all of the flexible material is withdrawn from the trough and consequently it is possible to read directly on the scale 16 the distance to which the ball would have been driven had it been free. As shown, the scale 16 goes up to 300 yards which ordinarily will be amply sufficient but if the ball should be given a prodigious blow the non-elastic strap 5 will be drawn taut and abruptly stop further flight of the ball.

40 45 I have found that the amount of rubber tube pulled out of the trough is reduced roughly proportionately according to the increased loft of the club which is used. In this manner, the distance indication is calibrated for club heads of different degrees of loft so that a substantially correct distance indication is given regardless of the club used. This action may roughly and partially be explained as follows: When the ball 6 is struck by a golf club having loft the force 50 giving it motion may be resolved into a horizontal component, and a vertical component which is proportional to the loft. The horizontal component acts directly toward pulling the flexible members out of the trough 1 but the vertical component acts toward making the ball describe a circular arc about an instantaneous center located at the point where the flexible members are leaving the trough. The vertical component, therefore, causes the ball 6 in swinging through 55 this arc, to beat down upon the ground, thus using up the force initially applied in a vertical direction by the loft of the club.

60 In order to stiffen trough 1, and also to prevent undue wear on the rubber tube 4 and aid in 70 re-seating the rubber tube 4, inside trough 1, the outer edges of the side walls 2 are flanged outwardly and also the right-hand ends of the side walls are beveled as shown.

65 If the ball has been struck squarely there is 75 no tendency for the trough 1 to move to right

or left and consequently the pointer 14 will point to the center of the scale 15 indicating that the ball was squarely hit. Should the ball have been hit to one side or the other it will, of course, start in this direction and in pulling the flexible elements 4 and 5 out of the trough, the trough will be turned on the pivot 3 in the direction in which the ball was hit and consequently the pointer 14 cooperating with scale 15 will indicate the number of degrees the ball was hit to the right 10 or to the left.

On short shots (in the range of 75 yards) the weight of the moving elements may be too great to permit pointer 14 to register much deflection on scale 15. Instead the direction of a short shot 15 is indicated by the direction in which the strip 5 and tube 4 point, when the ball 6 comes to rest after a short shot. It is obvious that the ball 6 will always tend to travel in the direction it is hit, and by actual test on short shots, strip 20 5 and tube 4 are found to come to rest in a position showing the approximate direction of flight of a free golf ball on short shots. The tendency of strip 5 and tube 4 to roll or travel sideways after ball 6 beats down against the ground after 25 being lightly hit for a short shot, is so slight, that the above is true.

If the ball is hit a glancing blow or if the club head is drawn across the ball while in contact with the ball, the latter will turn upon the stud 30 9 thereby causing the mark 12 which cooperates with the center or zero portion of the scale 13 to move to right or left thereby indicating, respectively, whether the ball was sliced or hooked. The purpose of the three stripes or marks 12 is 35 to equalize the wear on the ball. Thus after a given number of practice strokes the ball may be rotated 120° thereby bringing one or the other markers in line with the center portion of the scale.

40 It is desirable to have sufficient friction between the ball and the stud 9 so that no matter how badly the ball is hooked or sliced during a practice shot, it will not turn more than 180°. Otherwise it would be difficult to tell from the 45 arrangement shown whether the ball had been hooked or sliced. It will be obvious to those skilled in the art, however, that my invention is not limited to this particular arrangement and, if desired, any suitable equivalent means might 50 be employed for indicating which way the ball had been turned, even if it turned more than 180°.

I have found that the great difficulty in recording the amount of hook or slice imparted to a ball which is frictionally mounted on a vertical stud and decelerated as it travels along roughly parallel to the ground by a dragging action applied to the ball, is the fact that when the dragging action begins to retard the golf ball in flight the golf ball whips violently down against the 55 ground. This whipping action almost invariably causes a rotation of the ball relative to its stud. This, of course, results in a false indication of the amount of hook or slice. The problem to be solved is that the ball must be sufficiently free to rotate relative to the stud when it is teed up, but a moment later the ball must be effectively locked on the stud to prevent its turning relative to the stud head 11 when the ball beats down against the ground. With my invention this 60 problem is solved as follows: With the construction shown in Fig. 3 there is minimum pressure between the bottom surface of the head 11 of the stud and the golf ball when the stud is in a vertical position and the ball is ready to be struck. 65 70 75

This means that minimum friction is applied between bottom surface of stud head 11 and ball 6, when torque is applied to ball 6 in a teed up position. In other words, the "friction lock" between the bottom of the head 11 of the stud 9 and the ball 6 cannot apply at the moment the golf club hits the ball. Hence, the ball is not retarded in rotating relative to the stud at the moment of impact of the golf club head against the ball and the turning of the ball on the stud is largely limited by the friction of the shank of the stud against the ball. A moment later, however, retarding action due to the trough is applied to the flight of the ball, and the position assumed by stud 9 is approximately horizontal rather than vertical. In other words, at this time, the momentum of the golf ball is exerting a tremendous pressure against the bottom of the head 11 of the stud 9. This tremendous pressure is in force as the ball is whipped violently down against the ground and proves to be an effectual "friction lock" against the turning of the ball relative to the stud, as it beats down against the ground.

Although I have described my invention as including a trough 4, it should be obvious to those skilled in the art that my invention is not necessarily limited to this exact construction and other equivalent friction producing means might be employed. Thus, for example, portions of the trough 4 might be cut away to form the equivalent of a plurality of strips having inwardly sloping sides and consequently I intend to include all such equivalent constructions in the term "trough".

By the term "golf ball" as is used above, I do not necessarily intend to be limited to a construction such as would ordinarily be used in actually playing golf, but I intend to include any constructions which have substantially the same shape, size, resilience, etc., of an ordinary golf ball.

While I have shown and described a particular embodiment of my invention, it will be obvious to those skilled in the art that changes and modifications may be made without departing from my invention, and I therefore, aim in the appended claims to cover all such changes and modifications as fall within the true spirit and scope of my invention.

What I claim as new and desire to secure by Letters Patent of the United States is:

1. In combination, a metal trough, a rubber tube of substantially the same length as said trough placed longitudinally in said trough, a length of flexible material passed through said tube, and a golf ball fastened to one end of said length of material.

2. A game apparatus comprising, in combination, a pivotally mounted captive golf ball, and a plurality of substantially equally spaced marks thereon whereby said ball can be periodically rotated through an angle corresponding to the angle between said marks thereby to equalize the wear on said ball.

3. A game apparatus comprising, in combination, a pivotally mounted captive golf ball, a scale, a plurality of equally spaced marks on said ball, any one of which may serve at a time as a pointer for cooperation with said scale to indicate the amount of hook or slice imparted to said ball, whereby said ball can be periodically turned through an angle corresponding to the distance between two adjacent marks thereby to equalize the wear on said ball.

4. A game apparatus comprising, in combina-

tion, a captive golf ball pivotally mounted on a normally vertical pin, a mark on said ball, the friction between the ball and pin being sufficient to prevent more than one-half a turn of said ball on said pin as a result of a glancing blow from a golf club whereby it is always possible to tell from the direction of displacement of said mark whether said ball would have been hooked or sliced.

5. In combination, a length of flexible material, a golf ball, and means for fastening said ball to said length of material in such manner that if said ball is struck by a golf club so as normally to produce a hook or slice said ball will initially rotate on a normally substantially vertical axis through less than a half revolution and will thereafter be substantially locked from further rotation until brought to rest by the retarding action of said length of flexible material.

6. In combination, a length of flexible material, a golf ball, means for frictionally and pivotally mounting said ball on said length of material in such a manner that said ball can rotate about a substantially vertical axis when it is first struck by a golf club, and means for locking said ball against further rotation when said ball pulls against said length of material as a result of the translatory motion imparted to it by being hit by a golf club.

7. In combination, a length of flexible material, a normally vertical pin fastened to said length of material, a relatively large head on said pin, and a golf ball frictionally and pivotally mounted on said pin between said length of material and the head on said pin.

8. In combination, a golf ball, a normally substantially vertical stud of circular cross section passed through the center of said golf ball, said stud being tapered to a smaller diameter at the top than at the bottom, and having a relatively large flat head at the top.

9. In combination, a golf ball having a mark thereon, a normally substantially vertical stud passed through the center of said ball, a relatively large head on said stud, and a scale marked on said head for cooperation with the mark on said ball.

10. In combination, a relatively shallow metal trough having inwardly sloping side walls, means for pivotally supporting said trough at one end thereof for rotation in a horizontal plane, a scale marked off on the inside bottom surface of said trough, a collapsed rubber tube whose length is substantially the same as the length of said trough and whose width is greater than the minimum distance between the side walls of said trough placed longitudinally in said trough, a leather strap passing through said tube and extending from both ends thereof, the end of said strap remote from said pivotal supporting means being fashioned into a pointer, a transverse horizontal scale for cooperation with said pointer, a vertical steel pin fastened to the other end of said strap, a golf ball frictionally mounted on said pin, a mark on said golf ball, and a scale for cooperation with said mark.

11. In combination, a trough-like member, a length of flexible material normally fitted relatively snugly in said member and extending beyond one end of said member, and a golf ball fastened to the end of said length of material which normally extends beyond said member whereby if said golf ball is driven toward said member by a blow from a golf club said length of material will be frictionally retarded by the

sides of said member from being pulled out of said member.

12. In combination, a trough having inwardly sloping side walls, a length of flexible material whose normal width is greater than the shortest distance between the side walls of said trough placed lengthwise in said trough, means for fastening one end of said length of material to said trough, and means for fastening a golf ball

to the other end of said length of material whereby if said ball is driven toward the end of said length of material which is fastened to said trough by a blow from a golf club the friction produced by said length of material being pulled out of said trough between the side walls thereof serves to absorb the energy imparted to the ball.

JOHN K. STAFFORD.
